US0D1063929S

(12) **United States Design Patent** (10) **Patent No.:** **US D1,063,929 S**
(45) **Date of Patent:** **** Feb. 25, 2025**

(54) **NOTEBOOK COMPUTER**

(71) Applicant: **Shenzhen Chuangyingxin Industrial Co., Ltd.**, Shenzhen (CN)

(72) Inventor: **Liyang Li**, Guangdong (CN)

(**) Term: **15 Years**

(21) Appl. No.: **29/950,352**

(22) Filed: **Jul. 2, 2024**

(51) **LOC (15) Cl.** **14-02**

(52) **U.S. Cl.**

USPC **D14/327**; D14/315; D14/322

(58) **Field of Classification Search**

USPC D14/315-327, 345, 439-440; D3/900, D3/902

CPC G06F 1/1616; G06F 1/1601; G06F 1/1681

(57) **CLAIM**

The ornamental design for a notebook computer as shown and described.

DESCRIPTION

FIG. 1 is a front, right, and top perspective view of a notebook computer, showing my new design;

FIG. 2 is a rear, left, and bottom perspective view thereof;

FIG. 3 is a front elevational view thereof;

FIG. 4 is a rear elevational view thereof;

FIG. 5 is an enlarged left elevational view thereof;

FIG. 6 is an enlarged right elevational view thereof;

FIG. 7 is an enlarged top plan view thereof; and,

FIG. 8 is an enlarged bottom plan view thereof.

The broken lines in the drawings depict portions of the notebook computer that form no part of the claimed design.

1 Claim, 8 Drawing Sheets
